CLOTHES LINE SUPPORT AND TAKE-UP
DEVICE

Stephen James Max, Buffalo, N. Y.

Application November 9, 1936, Serial No. 109,998

1 Claim. (Cl. 68—3)

This invention relates to clothes line supports and take up devices and has for an object to provide a device of this character which may be readily mounted upon the wall of any convenient building such as a house or a garage, and will require minimum exertion to tension a clothes line when it is in service so that the wet clothes will be positively prevented from dragging on the ground.

10 A further object is to provide a device of this character which will be formed of a few strong simple and durable parts, which will be inexpensive to manufacture, and which will not easily get out of order.

15 With the above and other objects in view the invention consists of certain novel details of construction and combinations of parts hereinafter fully described and claimed, it being understood that various modifications may be resorted to 20 within the scope of the appended claim without departing from the spirit or sacrificing any of the advantages of the invention.

In the accompanying drawing forming part of this specification,

25 Figure 1 is a side elevation of a clothes line support and take up device constructed in accordance with the invention, parts being shown in section.

Figure 2 is a front elevation of the device.

30 Figure 3 is a vertical sectional view taken on the line 3—3 of Figure 1.

Referring now to the drawing in which like characters of reference designate similar parts in the various views, 10 designates a tube within 35 which a rod 11 is telescopically mounted. The tube 10 is provided with a longitudinal slot 12 which slidably receives a hook 13 that is attached to the upper end of the rod by a screw 14 or other connector. A cap 15 closes the upper end of the 40 tube 10 to prevent access of rain to the interior of the tube.

The tube 10 is mounted upon the wall 16 of a building such as a house or a garage by means of upper and lower strap brackets 17 and 18. The 45 upper strap bracket 17 embraces the upper end of the tube below the cap 15 and is provided with outturned legs 19 which are secured to the wall by screws 20.

The lower strap bracket 18 embraces the lower 50 end of the tube and is provided with comparatively long legs 21 which are provided with outturned ends 22 through which securing screws 23 are passed into the wall of the building. The

lower bracket 18 is longer than the upper bracket so that the lower end of the tube 10 is disposed a greater distance from the wall than the upper end and thus the tube inclines obliquely toward the building.

The rod 11 is provided with a grip 24 at the bottom, the same being formed by bending the rod at substantially a right angle. The grip also provides means for locking the device in operative position.

The locking device comprises a closed loop 25 formed of strap metal and having a substantially circular portion 26 at the bottom to receive the grip 24. The loop is straight for the major portion of its length to slidably fit the long legs 21 15 of the lower bracket 18, as best shown in Figure 3.

In operation, one end of the clothes line is attached to the hook 13 it being assumed that the other end is attached stationary to some suitable object. Before applying wet clothes to the line 20 the rod 11 is drawn downwardly through the instrumentality of the grip 24 until the hook 13 engages the lower end of the slot 12 as best shown in dotted lines in Figure 1. Thereupon the clothes are applied to the line and the line is 25 tensioned to take out sag by shoving the rod 11 upwardly through the instrumentality of the grip 24 until the hook 13 engages the upper end of the slot 12. The rod may now be locked stationary in its operative position by slipping the 30 locking loop 25 forwardly upon the legs 21 of the lower bracket until the eye 26 of the loop encircles the grip 24.

From the above description it is thought that the construction and operation of the invention 35 will be fully understood without further explanation.

What is claimed is:

A clothes line support and take up device comprising an outer tube having a longitudinal slot, 40 an inner rod, a hook on the upper end of the inner rod slidably fitted in said slot, upper and lower securing brackets attached respectively to the upper and lower ends of the tube, the lower bracket being longer than the upper bracket 45 whereby the tube may be mounted on a wall to incline upwardly and inwardly toward the wall, the lower end of the rod being bent at an angle to the rod to form a grip, and a strap loop encircling the lower bracket and adapted to be slipped over 50 the grip to lock the rod stationary at its upper limit of movement in the tube.
